METHOD OF LIQUEFYING GASES

Herbert Sixsmith, Reading, England, assignor to National Research Development Corporation, London, England, a corporation of Great Britain

Application April 8, 1953, Serial No. 347,513

Claims priority, application Great Britain April 22, 1952

7 Claims. (Cl. 62—175)

This invention relates to a method of and apparatus for liquefying gases, for example air.

It is known to liquefy gases by compressing the gas, expanding a part of it adiabatically, for example, in a turbine, and effecting heat exchange in a condenser between the expanded and the unexpanded parts so as to condense the latter, the whole of the compressed gas being first cooled by heat exchange with the expanded gas exhausted from the condenser. This method has the drawback that the mass flow of warm gas through the first stage heat exchanger or cooler is greater than that of the cold expanded gas exhausted from the condenser, so that the temperature difference between the expanded part and the compressed part at the cold end of the said cooler is undesirably large, resulting in a loss of efficiency.

Broadly stated, the invention consists of arranging for the net mass flow of compressed gas through the first stage heat exchanger or cooler to be substantially equal to the mass flow of expanded gas therethrough. In this way, maximum efficiency of heat exchange is obtainable, and the temperature difference between the incoming expanded gas and the effluent compressed gas is a minimum.

Since, however, the flow of expanded gas is equal to the total available compressed gas less the fraction liquefied (neglecting any losses due to condensation of water vapour and sublimation of CO₂), the above-mentioned balance of mass flow through the first stage cooler can only be achieved if a proportion, equal to the fraction to be liquefied, is divided off from the total available compressed gas flow and either caused to by-pass the cooler or, having passed through the cooler with the remainder, is recirculated therethrough in the reverse sense. In the latter case, the recirculating proportion is re-heated by the incoming gas, so that the net mass flow of compressed gas is substantially equal to the mass flow of expanded gas.

In the former case, the by-passing proportion may actually constitute the fraction to be liquefied, being supplied direct to the condenser; alternatively, the fraction to be liquefied is split off after the first stage cooler, and the equivalent proportion which by-passes the cooler is re-united with the balance of the compressed gas after this splitting off and before expansion. In the recirculatory system mentioned above, the fraction to be liquefied is also split off from the cooled compressed gas, but after division therefrom of the recirculatory proportion, and this proportion now re-heated, is reunited with the residual cold compressed effluent from the cooler before expansion.

Where the gas to be liquefied is a permanent gas, for example air, it is desirable to remove, at as early a stage as possible, those constituents, such as water and/or carbon dioxide, which solidify at the low temperatures involved. It is therefore convenient to arrange that the temperature at the cold end of the first stage cooler is such that the said constituents solidify in the cooler, and at least the compressed effluent from the cooler is dry. Where, however, the fraction to be liquefied, or an equivalent proportion thereto, by-passes the cooler, it is preferable to

2

ensure that the gas is dry either at the input to the compressor or at the point of division of the fraction to be liquefied or its equivalent proportion. This prevents the deposition of ice or solid CO₂ in the condenser on the one hand or in the turbine or other expansion device on the other. The recirculatory system mentioned above is thus seen to have an advantage over the other two alternatives according to the present invention, in that no special preliminary precautions are necessary to dry the gas.

Where the gas issuing from the cooler is expanded in a turbine, the temperature of this cooled gas is in certain cases lower than that at which maximum thermal efficiency can be obtained from the expansion stage. In such cases, it is preferred to adopt a system in which the balancing of the mass flows is achieved by splitting off a proportion of the compressed gas equivalent to the fraction to be liquefied, this equivalent proportion being already at, or then raised to, substantially the initial temperature and recombined with the cooled residual part of the gas which is to be expanded as this latter part passes to the expansion stage. The effect of this splitting off and recombination of an equivalent proportion is to raise the temperature of the gas entering the expansion stage.

The methods of the invention are efficiently operable at comparatively low pressures and the compressed gas may, for example, be at a pressure of between 8 and 15 atmospheres.

The heat exchanger used in the invention is preferably of the regenerative type, in which a number of chambers or compartments are successively opened to gas flow in appropriate directions by a valve device moving relatively to the said chambers or compartments (hereinafter called chambers for convenience) or to ducts serving them. At least one chamber is provided for the or each stream of compressed gas which is to flow through the regenerator, and for the stream of expanded gas. It is desirable that the total regenerator volumes provided for the expanded and the compressed gas should be in inverse ratio to the respective gas pressures. This would, however, involve providing an unduly large number of chambers for the expanded gas. A convenient compromise where, for example, the compressed gas is at a pressure of 8 atmospheres, is to provide two chambers for the expanded gas and one for the compressed gas being cooled. Where the mode of operation is such that the by-passing part of the gas is passed through the regenerator in reverse direction to the main stream of compressed gas, a further chamber is provided for this part. In addition, as described below, it is convenient to provide an additional chamber, making five in all, in which, during any one regenerative step, the requisite pressure is built up to enable the reverse flow of by-passing gas to take place therein in the next succeeding regenerative step.

Where the adiabatic expansion is effected in a single stage turbine it is necessary that this shall rotate at extremely high speeds. In certain types of turbine the force of the air jets impinging on the rotor vanes has a component capable of exciting radial oscillations of the rotor when adequate provision for the damping of such oscillations has not been made. The invention comprises a turbine adapted for use in the above-described methods, in which at least one main bearing for the rotor shaft is mounted on a member which is free to carry out small radial oscillations, and in which such member is provided with means for damping radial oscillations in a plurality of directions. Damping in two directions mutually at right angles in the circumferential direction may be sufficient, but in certain cases it may be preferable to provide an arrangement having damping in three or more circumferentially symmetrical directions. By this means it is possible to obtain adequate stability against the exciting component of force of the air jets. It is furthermore

an advantage of this arrangement that the amplitudes of oscillation of the rotor at the critical speeds are greatly reduced. The rotor shaft may be made long and slender, thus having a comparatively low heat conductivity. The bearings can thus be maintained at a temperature sufficiently high to enable them to be lubricated. The turbine is preferably of the axial flow impulse type.

The invention as applied to the liquefaction of air will now be particularly described with reference to the accompanying drawings, in which:

Figure 1 is a diagram illustrating the method of the invention, and

Figures 2 and 3 are diagrams illustrating modifications;

Figure 4 shows, in diagrammatic form, an apparatus for carrying out the method of the invention as shown in Figure 3; and

Figure 5 is a part sectional, part elevational view of a part of the axial flow impulse turbine used in the apparatus of Figure 4.

In Figure 1, an input stream of air A from a compressor and pre-cooler (not shown) (at a pressure of, for example, 8 atmospheres) is divided into first and second fractions or streams *a*, *b* respectively, and the first fraction *a* is passed through a first heat exchange stage or cooler E₁, from which it passes to an expansion turbine T provided with an air brake T₁. After leaving the expansion turbine, the expanded and cooled fraction enters a condenser E₂ from which it flows in reverse direction through the first stage cooler E₁ and thence to atmosphere. Since the expanded gas stream is wholly constituted by the compressed fraction *a* (neglecting losses due to condensation of water or sublimation of CO₂) the effective mass flows in opposite directions through the first stage cooler E₁ are substantially equal. The second fraction or stream *b* enters the condenser E₂ at atmospheric temperature. The temperature of the first fraction *a* leaving the turbine may be approximately 80° absolute, a temperature low enough to cause liquefaction of the compressed second fraction *b* in the condenser E₂. The liquid is expanded in a valve V₁ to atmospheric pressure and collected in a reservoir R from which it is tapped off at intervals through a valve V₂.

In Figure 2, a subsidiary stream or proportion *b*, equivalent in mass flow to the fraction *c* to be liquefied, is split off from the input stream A before the latter enters the cooler E₁ and passes to the turbine T. After leaving the first stage cooler E₁, the cooled compressed gas splits into the residual stream *a'* and the fraction *c* respectively. The proportion *b* is then recombined with the residual stream *a'*. Thus, carbon dioxide and water vapour are removed in E₁ from the residual stream *a'* and the fraction *c* before passage through the turbine T and the condenser E₂ respectively. Since the equivalent proportion *b* by-passes the first stage cooler E₁, it serves to warm the fraction *a'* so as to increase the expansion efficiency of the turbine.

In Figure 3, the equivalent proportion *b* is not split off from the input stream A until this has passed through the first stage cooler E₁. Carbon dioxide and water vapour are thus removed from it, and it is passed in reverse direction back through E₁ to be reheated before joining the residual stream *a'* entering the turbine T. The fraction *c* to be liquefied passes to the receiver R through the condenser E₂.

In each of Figures 1-3 the mass flow of the stream *b* is substantially equal to that of the air withdrawn as a liquid.

In the apparatus shown in Figure 4, the first stage cooler E₁ is constituted by a regenerator having five chambers A₁, A₂, A₃, A₄ and A₅. Connection to the warm ends of these chambers is made by means of a slowly rotating valve 1 (shown at their lower ends); and to the cold ends by means of automatic valves V₁-V₁₅. It will be understood that the valve member 1 is circular

in plan although it is shown for convenience in a schematic quasi-developed form.

The main stream of air from a compressor 2, in which the air is compressed to a pressure of, for example, 8 atmospheres, passes through a pre-cooling and cleaning stage 3 in which it is cooled to atmospheric temperature. In the position of the rotary valve 1 shown in Figure 4, the cooled compressed air passes by way of this valve, through the valve port P₁, in to the regenerator chamber A₁ in which it transfers its heat to the packing therein and is cooled nearly to the temperature of the expanded air stream leaving the condenser in the manner to be later described.

The stream of cooled compressed air now passes via the valve V₆, the manifold 4, and a restriction R₁ to the expansion turbine 5 in which it is cooled by adiabatic expansion. At D and B, respectively, an equivalent proportion *b* and the fraction *c* to be liquefied leave the main stream and accordingly, between points B and C, the stream constitutes the residual stream *a'* referred to in the description of Figures 2 and 3. The cold exhaust air from the turbine 5 passes through the pipe 6 to a condenser 7, in which it absorbs heat from the fraction *c* which reaches the condenser via pipe 8 and valve 9. The expanded fraction flows via the valves V₂ and V₃ to the regenerator chambers A₂ and A₃, and thence to atmosphere via the ports P₂ and P₃. The fraction *c* is liquefied by heat exchange with the expanded fraction in the condenser 7.

The equivalent proportion *b*, after leaving the main stream at D, flows through valve V₁₅ into the regenerator chamber A₅, through which it flows in reverse direction to the stream through the chamber A₁. After leaving the chamber A₅ through the port P₅, the stream *b* splits at X. The main part *b*₁ flows through a valve V_M and pipe 10 to join the stream *a'* at C. A subsidiary part *b*₂, controlled by a constant flow regulator 11, flows by way of a valve P₄ into the regenerator chamber A₄ in order to build up the pressure in this chamber for a purpose described below.

The rotary valve 1 slowly rotates so as, for example, to bring the port P₁ successively into line with the inlets of the regenerator chambers A₁ (as shown), A₅, A₄, A₃, A₂, A₁ etc. Thus the inflowing air from the pre-cooler 3 is passed, for a predetermined interval of time, through the chamber A₁, then for the same interval through the chamber A₅, and so on until finally it is again passed through the chamber A₁.

The function of the stream *b*₂ can now be explained. In the position of the rotary valve 1 next succeeding that shown in Figure 4, it will be necessary for the stream *b* to pass through the valve V₁₄ into the chamber A₄. In order to ensure that this valve is already opened, the regenerator chamber A₄ is slowly filled with dry air provided by the stream *b*₂. When the pressure in A₄ almost reaches the manifold pressure, the valve V₁₄ drops open by gravity.

The movable member of each of the valves V₁₁, V₁₂, V₁₃, V₁₄ and V₁₅ is provided with a cylindrical extension 32 constituting a piston which is slightly smaller in diameter than the tube 33 in which it is free to move. The annular space between the tube and the piston constitutes a restriction, and the pressure drop across the restriction tends to raise the piston, thus closing the valve. The value of the restriction is such that the valve remains open against the by-passing stream *b*, but closes when the flow slightly exceeds this value, as will happen in the case of V₁₄ when the port P₂ reaches A₄ and air from the manifold 4 rushes out to the atmosphere via V₁₄, A₄ and P₂.

Condensed liquid and a slight excess of gas are continually and automatically drawn off from the condenser 7 by means of an automatic expansion valve 12 which is adjusted to give an output pressure slightly above atmospheric pressure, so that the flow rate can be con-

trolled by means of an orifice 12a of normal dimensions. The liquid air is delivered to an automatic float trap 13 of conventional design, which discharges at intervals into a suitable receptacle. Excess air escaping with the liquid is returned to the turbine exhaust pipe 6 by way of a pipe 14.

It has previously been mentioned that a feature of the invention resides in the construction and design of the expansion turbine 5. In the apparatus of Figure 4, the turbine is an axial flow impulse turbine, the rotor, stator, shafting and one bearing of which are shown in Figure 5. A shaft 15 upon which is mounted the rotor 16 also carries a centrifugal blower 17 which acts as the brake 18 shown in Figure 4. The blower is shown as a schematic block in Figure 5, since its design forms no part of the present invention. It may have the form of a drum having radial holes for air flow. High pressure air is fed via the inlet 19 to the stator blades 20 having a shroud ring 21 shrunk thereon to avoid tip leakage. A turbine according to the invention has been constructed, in which the turbine rotor is machined from a solid piece of brass and having a tip diameter of about $\frac{5}{8}$ ", the rotor blades being about $\frac{1}{16}$ " long and having a chord width of $\frac{1}{4}$ ". The shroud ring is of brass and the rotor is mounted on the shaft 15 which is of silver steel having a diameter of $\frac{3}{32}$ ". This shaft is about 4" long and is mounted in cup bearings at each end. The shaft 15 is machined conically at its end which seats in balls 22 located in the cup 23; the stalk 24 of the cup being hollow to allow for the passage of oil to the bearing.

An annular shoulder of the cup 23 bears on a radial compression spring 25, which in turn bears on the bottom of a cup 26. This spring 25 takes up the normal amount of differential expansion and effectively maintains a substantially constant load on the ball bearings thereby preventing play between the conical end of the shaft and the outer case of the bearing. A stem 27 integral with the cup 26 passes through an externally threaded sleeve 28 as shown, which sleeve is adapted to pass through a hole in the outer case (not shown) and to have a nut screwed thereon to support the shaft and bearing assembly within the casing. The stem 27 is hollow, its bore communicating with the bore through the hollow stalk 24 for the supply of oil thereto.

A small clearance is allowed between the cup 26 and the internal wall of the sleeve 28. Thus the bearing as a whole is capable of radial displacement, which is damped by means of two oil-filled dashpot mechanisms of which only one (29) is shown in the drawing and which are mutually at right angles. These dashpots are of conventional design, and the piston rods 30 are connected to the cup 26 through a close-fitting ring 31. The bearing at the other end of the shaft 15 may be similarly constructed or, alternatively, may be similar except that no allowance is made for radial displacement.

In an alternative construction of the turbine, the cup 26 may be replaced by a sliding collar to which are attached the piston rods of three-dashpots at 120° to each other. In another construction, the piston rods are secured to the stem 27 instead of being attached to the cup 26.

If the regenerator chambers A₁ to A₅ are to be of the small size necessary to keep the bulk of the machine as small as possible, they require a packing material which is efficient and simple to construct and has a high conductivity in the direction transverse to the direction of flow therethrough. A low thermal conductivity in the direction of the flow is desirable. In the present invention, it is preferred to use a packing consisting of discs of fine wire gauze, which discs are separated by discs of thermally insulating material such as cloth of open weave, for example, rayon net.

What I claim is:

1. The method of liquefying a gas comprising com-

pressing the gas, dividing the compressed gas into two parts, a major part and a minor part, passing at least the major part through a first stage cooler to cool it, dividing the major part, after such cooling into two parts, a small part and a large part, after such division passing the small part through a condenser to liquefy it and after such division combining the large part with the minor part which is uncooled, expanding the combined parts adiabatically accompanied by the expenditure of energy to reduce their temperature, and passing the expanded combined parts first through the condenser in counterflow with respect to the small part liquefied therein and secondly through the first stage cooler in counterflow with respect to the compressed gas flowing through it, the mass flow per unit time of compressed gas flowing in one direction through the first stage cooler being substantially equal to the mass flow per unit time of gases passing through the first stage cooler in the other direction.

2. The method according to claim 1 wherein the division of the compressed gas into the major part and the minor part takes place before passing through the first stage cooler, the minor part being expanded as aforesaid along with the large part of the major part, without the minor part passing through the first stage cooler.

3. The method according to claim 1 wherein the whole of the compressed gas is passed through the first stage cooler before division into the major part and the minor part, the minor part being then passed through the first stage cooler in counterflow with respect to the said whole of the compressed gas where the minor part is restored to the uncooled condition before expansion along with the large part.

4. The method according to claim 1 wherein the said expanded combined parts are combined with vapour rising from the surface of the liquefied gas before passing through the condenser in counterflow as aforesaid.

5. The method according to claim 2 wherein the said expanded combined parts are combined with vapour rising from the surface of the liquefied gas before passing through the condenser in counterflow as aforesaid and wherein the mass flow per unit time of the expanded combined parts together with the said vapour, passing through the first stage cooler in counterflow as aforesaid, is substantially equal to the mass flow per unit time of the major part which passes through the first stage cooler.

6. The method according to claim 3 wherein the said expanded combined parts are combined with vapour rising from the surface of the liquefied gas before passing through the condenser in counterflow as aforesaid and wherein the mass flow per unit time of the expanded combined parts together with the said vapour, passing through the first stage cooler in counterflow as aforesaid, is substantially equal to the mass flow per unit time of the whole of the compressed gas passed through the first stage cooler as aforesaid minus the mass flow per unit time of the minor part.

7. The method according to claim 1 wherein the expansion of the said combined parts is effected in an impulse turbine from which the expanded combined parts emerge at a temperature at least a few degrees above their liquefaction point.
